UNITED STATES PATENT OFFICE.

ALFRED P. KIVLIN, OF NEW YORK, N. Y., ASSIGNOR TO H. J. FORSTER, TRUSTEE OF THE AMERICAN RAILWAY ASSOCIATION.

METHOD OF AND APPARATUS FOR CRATING FURNITURE.

Application filed January 21, 1927. Serial No. 162,451.

This invention relates to methods of and apparatus for crating furniture.

Many articles of furniture are damaged in shipment due to the fact that although the articles are crated, the weight thereof is borne by the legs. Because of the severe handling to which the crates are subjected, the legs are broken.

This invention has for its salient object to so crate or package furniture or similar articles that the weight of the articles will be borne by the crates.

Another object of the invention is to provide a method of crating or supporting furniture in such a manner that the supporting means cannot mar or deface the finished surfaces of the furniture.

Another object of the invention is to provide a method of crating furniture for shipment in such a manner that the crating will be facilitated and expedited.

Further objects of the invention will appear from the following specification taken in connection with the drawings, which form a part of this application, and in which

Fig. 1 is a sectional elevation illustrating one method and form of device for crating furniture;

Fig. 2 is an end elevation of the crate shown in Fig. 1;

Fig. 3 is an enlarged sectional elevation illustrating one form of blocking for preventing the suspending means from engaging and marring the finished surfaces of the furniture;

Fig. 4 is a perspective elevation of the blocking;

Fig. 5 is a sectional elevation similar to Fig. 1 illustrating the method of crating an article having ornamental or scroll work;

Fig. 6 is an end elevation of the structure shown in Fig. 5;

Fig. 7 is an enlarged elevation similar to Fig. 3, but showing another form of blocking for preventing the suspension means from engaging and marring the finished surfaces of the article; and

Fig. 8 is a perspective view of the blocking shown in Fig. 7.

The invention briefly described consists of a method of and apparatus for crating or packaging furniture or similar articles in such a manner that the weight of the article will be borne by the crate. The gist of the in-

vention consists of suspending the article on suitable supporting means, such as wires which extend over the top of the crate, downwardly along the side and beneath the article, thus suspending the article and supporting it on the crate whereby the weight will not be carried by the legs of the article. Blocking or other suitable means is utilized for preventing the supporting wires from engaging and marring or defacing the finished surfaces of the article. Further details of the invention will appear from the following description.

Any suitable form of crate may be utilized and in the form of the invention illustrated, there is shown a crate having a top 10, bottom 11 and sides comprising a front 12, back 13 and ends 14 and 15. The crate may be braced in any desired manner and as illustrated, has transverse side braces formed by members 16, 17 and 18.

In Figs. 1 to 4 inclusive, there is shown a chiffonier 20 disposed within the crate, the top 21 of the chiffonier being disposed beneath the top 10 of the crate. Suitable packing 22 of felt or other material may be interposed between the top of the chiffonier and the top 75 of the crate.

The chiffonier 20 as illustrated has legs 25 and 26 but the article is supported in such a manner that the legs do not bear the weight 85 thereof. This is accomplished by means of flexible supporting means, such as wires 28 and 29, which extend across the top members 30 and 31 of the crate, downwardly along the ends 14 and 15 and beneath the transverse 90 members 18. It will be understood that any other form of flexible supporting means may be used, such as metal straps, wire or rope, cables and so forth.

In order to prevent the wires from engaging and marring the finished lower edges 35 of the article, blocking is interposed between the wires and these surfaces. This blocking may have any desired form or shape but in the form of the invention shown particularly 100 in Figs. 3 and 4, the blocking consists of a pair of strips 36 and 37 secured together and so dimensioned as to fit under the bottom of the chiffonier and beneath the surfaces 35 as shown in Fig. 3.

When the ends of the wires 28 and 29 are connected together and twisted, the weight of the chiffonier will be supported on the wires.

This can be conveniently accomplished by crating the furniture upside down.

The structure shown in Figs. 5 to 8 inclusive is similar to that already described. In these figures, however, the chiffonier is illustrated as having ornamental or scroll work 40 and 41 at the top and bottom thereof and similar scroll work 42 at the ends of the bottom. In this case, the top 45 of the chiffonier 10 is supported against cross pieces 46 and 47.

The wires as in the other embodiment extend across the cross strips 30 and 31 of the top crate, down the ends or sides 14 and 15 and beneath the transverse strips 18.

15 The blocking in this instance consists of a pair of board strips 50 and 51 secured together in T-shape so as to space the wire away from the scroll work 42 at the ends of the bottom of the furniture. In this case as in

20 the preceding embodiment, the furniture can most conveniently be crated upside down and the wires can be twisted and placed under sufficient tension to support the article. Any suitable form of mechanical device may be 25 used for securing and tensioning the wire or metal straps. For instance, wire tying devices are very efficient and by means of such devices, the wire can be quickly and easily secured with a minimum amount of labor.

30 From the foregoing description it will be clear that the method and apparatus described will so support furniture or any other desired article that the weight of the article will not be borne by the legs thereof. In this manner, breakage of the article shipped is materially reduced and the liability of breakage is reduced to a minimum.

Although certain specific embodiments of the invention have been particularly shown and described, it will be understood that the invention is capable of modification and that changes in the construction and in the arrangement of the various cooperating parts 40 may be made without departing from the

spirit or scope of the invention, as expressed 45 in the following claims.

What I claim is:

1. In combination, a furniture crate having a top, longitudinal and transverse side members and a bottom, and flexible means for suspending the article to be crated extending across the top, down the sides and through the crate beneath the article in supporting position with respect thereto. 50

2. In combination, a furniture crate having a top, longitudinal and transverse side members and a bottom, flexible means for suspending the article to be crated extending across the top, down the sides and through the crate beneath the article in supporting position with respect thereto, and spacing and 60 protecting means between the flexible means and finished surfaces of the article. 65

3. In combination, a furniture crate having a top, longitudinal and transverse side members and a bottom, certain of the transverse side members being spaced above the bottom of the crate, and wires extending across the outside surface of the top of the crate, down the sides of the crate, beneath the transverse members above the bottom of the plate, through the crate and beneath the article to be suspended and supported thereby. 70

4. In combination a furniture crate having a top, longitudinal and transverse side members, and a bottom, wires for suspending the article to be crated extending across the top, down the sides and through the crate, beneath the article in supporting position, with respect thereto, spacing and protecting block between the flexible wires, and the finished surfaces of the article, and protecting felts between the sides of the crate and the finished surfaces of the article. 75 80 85

In witness whereof, I have hereunto set my hand this 18th day of January, 1927.

ALFRED P. KIVLIN.
